Specification for Design.

Patented Aug. 30, 1921.

Application filed January 22, 1921. Serial No. 439,294. Term of patent 3½ years.

To all whom it may concern:

Be it known that I, FREDERICK A. FRERICHS, a citizen of the United States, residing at Philadelphia, in the county of Philadelphia and State of Pennsylvania, have invented a certain new and ornamental Design for an Electric Ceiling-Fixture, of which the following is a specification, reference being had to the accompanying drawing, forming part hereof.

Figure 1 is a perspective view of an electric ceiling fixture, showing my new design.

Fig. 2 is a bottom plan view of the plate as shown in the fixture.

I claim:

The ornamental design for an electric ceiling fixture, as shown.

FREDERICK A. FRERICHS.
